UNITED STATES PATENT OFFICE.

SIDNEY W. FARNSWORTH, OF PITTSBURGH, PENNSYLVANIA, ASSIGNOR TO WESTINGHOUSE ELECTRIC AND MANUFACTURING COMPANY, A CORPORATION OF PENNSYLVANIA.

ANODE STRUCTURE FOR VAPOR-CONVERTERS.

1,226,069.

Specification of Letters Patent. Patented May 15, 1917.

Application filed July 12, 1915. Serial No. 39,362.

To all whom it may concern:

Be it known that I, SIDNEY W. FARNSWORTH, a citizen of the United States, and a resident of Pittsburgh, in the county of Allegheny and State of Pennsylvania, have invented a new and useful Improvement in Anode Structures for Vapor-Converters, of which the following is a specification.

My invention relates to anode structures for vapor converters, and it has for its object to provide an anode that shall be free from leaks, that shall produce and maintain a suitable rectifying arc without the liberation of occluded gases and the temperature of which may be readily adjusted.

Referring to the accompanying drawings, Figures 1 and 2 are front and side views, respectively, partially in section and partially in elevation, of an anode embodying my invention; Fig. 3 is a fragmentary view, partially, in section and partially in elevation, of an anode embodying a modification of my invention; and Figs. 4, 5 and 6 are side views, partially in section and partially in elevation, of vapor converters embodying still further modifications of my invention.

In the operation of vapor electric apparatus, such, for example, as vapor converters, it is necessary that an extremely high vacuum be maintained within the device, and, consequently, all portions of the container wall, such, for example, as the anodes, must be substantially impervious to the passage of gases. The problem of providing an anode of the character described is rendered difficult by reason of the fact that, in the successful operation of a converter, the temperature of the anodes must be accurately controlled by the circulation of a cooling medium therethrough, opportunity for possible leaks being therefore provided. The difficulties of the above-described problem are rendered still greater because of the fact that it is frequently necessary to provide anodes which shall have exceedingly irregular and unusual shapes in order to adapt them for operation with highly specialized forms of shielding means or for other reasons. Special modifications of this character must generally be assembled by welding, brazing or soldering and are therefore exceedingly difficult to produce and maintain in the desired vacuum-tight condition.

I have found that all of the above-men-

tioned difficulties may be surmounted, and a tight and effective anode of almost any desired configuration may be produced by suitably bending and shaping pieces of seamless tubing, all joints and welds preferably being maintained outside the container and nothing but a loop of the tubing being exposed to the vacuum. Tubing of the character described may be readily bent and formed into a wide variety of shapes, and, even when so bent, it is impervious to the passage of liquids and gases and it, in itself, provides ample circulating space for a temperature-regulating medium.

In the operation of vapor converters, I have found that ordinary "treating-out" processes in a great many cases remove the occluded gases from only the small portion of the anode most directly exposed to the effects of the treating-out arc. In an ordinary converter wherein the anodes depend from the cover of the container and terminate in a downwardly extending portion, said lower portion is most directly exposed to the action of the arc and hence is the only portion of the anode that has the occluded gases thoroughly removed therefrom. When starting a converter into operation or when passing an excessive amount of current therethrough, there is a tendency of the arc to wander up on the relatively untreated portions of the anodes and to liberate occluded gases therefrom, thus causing erratic and uncertain action. I do not desire to restrict myself to any specific theory in explaining this action, but it appears to have a thermal origin, the heating effects of the arc, in a comparatively cool container or when carrying an abnormal amount of current, being such as to cause it to rise on the side of the anode. The natural course to be followed in remedying this difficulty would be to cause the anodes to project up through the bottom of the container and terminate in an upwardly extending portion, so that thermal effects at no time would tend to cause the arc to pass to untreated portions of the anode. The difficulties in properly insulating and sealing an anode of the type indicated are very great, however, and I therefore propose to provide anodes depending from the cover and terminating in transversely and upwardly extending terminal members, roughly following the shape of a J. By suitable

shielding means, the arc may be prevented from impinging upon the long stem or upon the bent portion of an anode of the character described and be restricted solely to 5 the upwardly extending terminal portion thereof. I find that the use of seamless steel tubing for anodes lends itself very readily to this type of construction and may be bent to conform to any desired anode 10 shape or special shielding system.

In the development of my invention, I have found that steel tubing is not, at all times, entirely suitable for directly supporting a power-converting arc and that better 15 results may be obtained by employing some such material as copper or graphite as the arc-supporting material. By molding or otherwise mounting materials having the desired characteristics upon the steel tubing 20 forming the essence of my invention, a composite anode is provided having many desirable characteristics. The arc-supporting material need have but little mechanical strength and it may, if desired, be highly 25 porous in nature as mechanical strength and vacuum maintenance are both provided to a high degree by the seamless tubing members.

Referring to the accompanying drawing 30 for a more detailed understanding of my invention, I have shown in Figs. 1 and 2, one of the simplest forms of my invention. A piece of tubing 7, preferably consisting of seamless steel, is formed into a pipe or 35 loop and said loop is bent upwardly and backwardly so as to form a downwardly extending central portion 8 surmounted by a substantially annular ring 9. The tube 7 is sealed through and insulated from the cover 40 of an evacuated container by means of a joint 11 of any desired or suitable form, such as is shown in detail in a copending application of David E. Carpenter, Serial No. 38,117 filed July 6, 1915, and assigned to the 45 Westinghouse Electric & Manufacturing Company. In operation, the power-converting arc plays upon the lower portion 8 and the temperature thereof is maintained at a reasonable figure by means of a cooling fluid, 50 such, for example, as water, which is caused to flow through the interior of the tube 7. The portion 9, while not operating to directly support the arc under normal conditions, in a measure controls the temperature 55 of the space surrounding the anode and this tends to insure stability of operation.

Referring to the form of my invention shown in Fig. 3, a tube 7, similar to that shown in Fig. 1, is shown embedded in a 60 mass 12 of copper, graphite or other suitable arc-supporting material. The mass 12 may be of a refractory porous nature, wholly unsuited to produce an anode having great mechanical strength or resistance to gas 65 leakage, but the tubing 7 provides these

essential requisites and maintains the temperature of the mass 12 within desired limits.

In Fig. 4 I have shown the container of a vapor converter at 13 provided with a cathode 14 and with an anode 15 projecting through the cover thereof and surrounded by a suitable insulating joint 16. The anode 15 comprises a loop of tubing 7 which depends for a considerable distance from the cover, is then bent transversely and terminates in an upwardly extending portion. All portions of the tubing 7 within the container, except the terminal bend, are shielded by a suitable member 17. In operation, a power-converting arc is required to follow 7 some such path as that indicated by an arrow 18, impinging down upon the anode 15. Under all conditions, the thermal arc-shifting actions are such as to cause the arc to remain upon this portion of the anode structure. The terminal bend of the anode 15 may be made of such size and shape that it is readily treated out in the process of manufacture, and subsequent suitable operation is thereby insured.

A still more positive method of causing the power arc to assume a downward direction and to impinge upon an upwardly extending anode portion is shown in Fig. 5 wherein the general anode structure is the same as in the Fig. 4 but the cathode 14 is provided with an upwardly extending arc-controlling ring 19 composed of quartz or other suitable refractory material. The operating anode spot is maintained within the ring 19 by a suitable keep-alive anode 20, and the active portion of the anode 15 is exposed outside of, and below, the upper edge of the ring 19. The power arc is thus forced to take some such path as that indicated by 1 the arrow 21, with the attainment of the desired ends. The terminal bend of the anode in Fig. 5 is provided with a mass of arc-supporting material, as described in connection with Fig. 3.

In Fig. 6 I have shown a loop of tubing 7 having the general shape shown in Figs. 1 and 2 and supported from the cover of a vapor converter 13. The vertically disposed supporting stems are shielded by a suitable shell 22, and the lower surface of the portions 8 and 9 is shielded by a suitable refractory insulating bowl 23, so that the arc is required to follow some such path as that indicated by an arrow 24 and to impinge 1 upon the upper surface of the annular ring 9. The bowl 23 may, if desired, be provided with a minute perforation 25 in the bottom thereof to permit the escape of condensed 1 mercury.

In addition to the features which have been pointed out, attention is drawn to the fact that, in the structures shown in Figs. 4, 5 and 6, effective means are provided for preventing mercury globules thrown off by 1

cathode blast from impinging upon the active portions of the anodes, with resultant short circuiting or reverse arcing.

While I have shown my invention in its simplest and preferred forms, it will be obvious to those skilled in the art that it is susceptible of various minor changes and modifications without departing from the spirit thereof and I desire, therefore, that no limitations shall be placed thereupon except such as are imposed by the prior art or are specifically set forth in the appended claims.

I claim as my invention:

1. An electrode for vapor-electric apparatus comprising a loop of tubing composed of impervious material, means for circulating a temperature-regulating medium therethrough, and a mass of arc-supporting material mounted thereupon.
2. An electrode for vapor apparatus comprising a mass of pervious arc-supporting material, and means for circulating a cooling medium therethrough without permitting the passage of gas from said medium into said arc-supporting material.
3. In vapor-electric apparatus, the combination with an electrode provided with a gas-free portion, and means for restricting the operating arc to said gas-free portion.
4. The combination with an evacuated

container, of an electrode therein comprising a member projecting downwardly through the upper portion thereof, bending transversely and terminating in an upwardly extending portion and a coöperating electrode.

5. In a vapor converter, an anode depending from the cover and having substantially a J shape and means for maintaining an arc on the terminal portion thereof from a co-operating electrode.

6. In a vapor converter, an anode comprising a loop of tubing projecting through, and depending from, the cover and bent to substantially a J shape and means for maintaining an arc at the terminal portion thereof from a coöperating electrode.

7. In a vapor converter, an anode comprising a loop of tubing projecting through, and depending from, the cover and bent to substantially a J shape, a mass of arc-supporting material on the terminal portion thereof, and means for maintaining a power-converting arc upon said material from a co-operating electrode.

In testimony whereof, I have hereunto subscribed my name this 28th day of June 1915.

SIDNEY W. FARNSWORTH.
